TOOL FOR REMOVING OR INSERTING BUSHINGS, BEARINGS OR THE LIKE

Filed Sept. 29, 1934

UNITED STATES PATENT OFFICE

2,036,782

TOOL FOR REMOVING OR INSERTING
BUSHINGS, BEARINGS, OR THE LIKE

André Ullmo, Cleveland, Ohio

Application September 29, 1934, Serial No. 746,051

1 Claim. (Cl. 29—83.2)

This invention relates to a tool for removing bushings, bearings or the like from inaccessible places. The tool is particularly adaptable for removing the bearings from the end plate of an electric motor. It is also adaptable for inserting the valve guides of an internal combustion engine.

The main object of the invention is to provide a tool of the character described which consists of few parts, and which can be manufactured at low cost and which are readily assembled and disassembled.

A further object of the invention is to provide a tool of the character described which is provided with adapters and connections for accommodating the device for use for the different purposes set forth.

Further and more limited objects of the invention will appear as the description proceeds and by reference to the accompanying drawing in which Fig. 1 is a view in side elevation of my improved tool; Fig. 2 is a vertical sectional view of the tool shown in Fig. 1, showing the tool being used to remove a bushing or bearing; Fig. 3 is a view similar to Fig. 2 showing how the tool 20 is used to insert a bushing or bearing in place; Fig. 4 is a vertical sectional view on the line 4—4 of Fig. 2; Fig. 5 is a view of the same tool having a member detachably secured thereto to adapt it for use for removing a bearing from inaccessible places and Fig. 6 is a fragmentary detail sectional view showing the manner in which the extensions are applied to the rod.

Referring now to the drawing, the tool consists essentially of a body member 1 which is preferably cylindrical in shape and provided with a hollow sleeve-like extension 2. Extending axially of the body member 1 is an opening 3 through which extends a rod 4 having a threaded portion 5 adjacent one end. The opposite end of the rod 40 is somewhat reduced in diameter as shown at 6 and is provided with a threaded end portion 7 adapted to receive thereover a tap 8 which is provided with a shoulder adapted to be inserted within the end of a bushing or bearing, as shown in Fig. 2. The rod 4 is slidably mounted within the opening in the body member and is held against rotation with respect thereto by means of a key 9. Threadedly secured over the opposite end of the rod 4 is a nut 10 in which are threadedly secured a pair of arms 11 and 12 by means of which the nut may be turned. It will be clear that rotation of the nut 10 will cause an endwise movement of the rod 4 with respect to the body member 1.

The reference character 13 indicates a member

in which it is desired to remove or insert a bushing or bearing which is indicated by the reference character 14. When the tool is to be used to remove a bearing, the parts are moved to the position shown in Fig. 2 so that the reduced end of 5 the rod projects beyond the end of the bearing. The tap 8 is then threadedly secured to the reduced end portion 7 of the rod and the nut 10 then turned by means of the arms 11 and 12 to pull the bearing toward the left as seen in Fig. 2 10 into the hollow end portion 2 of the body member 1. When it is desired to insert a bearing in place, the parts are moved to the position shown in Fig. 3 and the bearing 14 is then secured over the extending end portion of the rod and the 15 tap 8 secured in place. The nut 10 is then turned to force the bushing up into the member 13.

In order to adapt the tool for use in removing bushings or bearings from inaccessible places, such as from connecting rods or pistons, I provide a sleeve-like extension or adapter 15 which fits into the end portion 2 of the body member. I also provide an extension rod 16 which is threadedly secured to the reduced end 7 of the rod 4 by means of a coupling member 17. The 20 outer end of the extension rod 16 is provided with an enlarged head portion 8'. I furnish with the tool one or more adapters 15 and extensions 16 whereby to adapt the tool for use for purposes 25 hereinbefore described. In Fig. 6 there is disclosed an extension rod 19 having a threaded socket 20 and a reduced threaded end portion 21 adapted to receive a tap 8 thereover.

The end of the body member 2 adjacent the nut 10 is knurled as shown at 18 so that it may 35 be more readily gripped in the hand. It is of course understood that I supply with the tool a number of taps 8 adapted to fit the different sized bearings or bushings.

It will now be clear that I have provided a tool of the character described which will accomplish the objects of the invention hereinbefore stated. It is to be understood that the embodiment of the invention herein disclosed is merely 40 illustrative and is not to be considered in a limiting sense as various changes may be made without departing from the spirit of my invention. It is therefore understood also that I furnish with the tool a number of taps 8 of different 45 sizes and that these taps may have a tapered shouldered portion to fit different sized bearings or bushings. It is therefore to be understood that the invention is to be limited only in accordance with the scope of the appended claim.

Having thus described my invention, what I claim is:

A tool for removing or inserting bushings, bearings or the like comprising a body member having an axially disposed opening therein, a threaded rod slidably mounted in said body member and made up of a plurality of sections and held against rotary movement with respect thereto, a nut threadedly engaging said rod for moving the same endwise with respect to said body member,

and a tap detachably secured to the outer end of said rod adapted to engage a bushing, bearing or the like, said nut having a pair of arms thereon by means of which it may be manually operated, and an adapter detachably secured within the end of said body member and having a hollow reduced sleeve-like extension thereon, said tap having a shoulder thereon adapted to engage a bushing, bearing or the like.
